[57] CLAIM

The ornamental design for a motorcycle instrument housing, as shown and described.

DESCRIPTION

FIG. 1 is a front perspective view of a motorcycle instrument housing showing my new design.

FIG. 2 is a top plan view thereof.

FIG. 3 is a rear elevational view thereof.

FIG. 4 is a front elevational view thereof.
FIG. 5 is a side elevational view thereof with the opposite side being the mirror image.

FIG. 6 is a front perspective view of a motorcycle instrument housing showing a second embodiment of my new design.

FIG. 7 is a top plan view of FIG. 6.

FIG. 8 is a rear elevational view of FIG. 6.

FIG. 9 is a front elevational view of FIG. 6.
FIG. 10 is a side elevational view of FIG. 6 with the opposite side being the mirror image.

The broken line showing of a motorcycle gas tank in FIGS. 1 and 6 of the drawing is for illustrative purposes only and forms no part of the claimed design.
